MAGNETIC SEPARATING DEVICE

Robert H. Butters, Atlanta, Ga.

Application April 15, 1939, Serial No. 267,990

2 Claims. (Cl. 209—223)

This invention relates to improvements in magnetic separating devices of the kind which are employed to remove metal objects from material which may accidentally include them, whereby to prevent damage to the machines to which the material may be delivered for processing.

Apart from the miscellaneous assortment of metal objects ordinarily requiring separation and which do not present a serious problem, it frequently occurs that the material to be processed includes ball bearings which have escaped from the raceways in the machines which have previously acted upon it. Such bearings are extremely hard and hence highly destructive. However, owing primarily to their speed of travel and to the small areas which they present to the surfaces over which they roll, the separating devices heretofore employed have proved ineffective in preventing their passage to the machines to be protected.

The principal object of the present invention, therefore, is to overcome the above objection, this object contemplating a device which is so designed that both poles of the magnetic means exercise simultaneous attractive forces upon bearings or other similarly shaped objects which roll upon it, which combination of forces in conjunction with the physical characteristics of the device insure arresting and permanent retention of the bearings or other objects regardless of their size or the angle at which the device is arranged without impeding the flow of the material to be processed.

A further object is to provide a self-contained device which requires no outside source of electrical energy and which is capable of retaining its magnetism indefinitely without attention.

A still further object is a novel design and arrangement of the parts of the device whereby compactness and simplicity and economy in construction are obtained.

The invention is illustrated in the accompanying drawings in which:

Figure 1 is a sectional view of a linter having a device embodying the features of the invention associated therewith.

Figure 2 is a horizontal sectional view taken along line 2—2 of Figure 1.

Figures 3, 4 and 5 are fragmentary sections taken along lines 3—3, 4—4 and 5—5, respectively, of Figure 2.

Figures 6 and 7 are sectional views at right angles with respect to one another and are taken along lines 6—6 and 7—7, respectively, of Figure 3.

Figure 8 is an enlarged fragmentary sectional view, generally similar to Figure 5, illustrating the manner in which ball bearings of various sizes are engaged by both poles of the magnetic means.

The invention is illustrated, by way of example, in connection with a cotton seed linting machine, the latter being sufficiently illustrated for the purpose in view by a showing of the hopper 10, feed roll 11, roll box 12 and angularly inclined wall 13 down which the seeds flow by gravity from the hopper to the roll box as the feed roll is rotated intermittently in accordance with conventional practice.

The wall 13 may be of wood, as shown, or of any other suitable material. Preferably it is formed with a shallow horizontally extending recess 14 in which a pair of bars 15 are secured in spaced relation by screws 16, the depth of the recess 14 being predetermined so that the upper faces of the bars are substantially flush with, and provide continuations of, the upper face of the wall. The bars extend the full width of the wall crosswise of the direction of the flow of the seeds. In accordance with the invention a division strip 17 of insulating material is arranged between the bars. The space between the bars is relatively narrow and said strip co-operates with the bars to provide a shallow recess between them, the upper face of the strip being inset with respect to the upper faces of the bars a distance which will permit ball bearings of various sizes, and similarly shaped objects, to enter the narrow recess far enough to insure their simultaneous contact with the opposing edges of both of the bars, as best shown in Figure 8, without impeding the flow of the material to be processed.

A series of openings 18, each of which communicates with the recess 14, is formed in the wall 13. The said openings are preferably uniformly spaced and are adapted to accommodate any desired number of permanent magnets 19, the latter being arranged so that all of their positive terminals contact one of the bars 15 and all of their negative terminals contact the other bar. The bars, therefore, provide pole pieces of opposite polarity, the strength of the magnetic field which they set up depending, of course, upon the combined strength of the magnets. In order to maintain the stability of magnetic field thus provided it is preferred that the bars 15 be connected at one or more points by keepers 20. The latter are rectangular in cross section. They fit in elongated slots 21 (Figure 7) formed in the wall 13 between the openings 18; they are located be-

tween pairs of the magnets 19 behind the division strip 17; and they are held by attraction against the under faces of the bars. A cross-piece 22, which is secured to the under side of the wall 13, co-operates with the latter, the bars and the division strip, to completely enclose the magnets and keepers.

From the foregoing it will be apparent that all of the cotton seeds delivered to the roll box are first caused to pass over the bars 15. Hence any metal objects included in the seeds will be attracted by the bars and prevented from entering the roll box. In the event that a ball bearing is included in the seeds its rate of movement will be initially retarded as it rolls over the upper bar toward the slot between the latter and the lower bar. As it partially enters the slot and contacts the upper edge of the lower bar while maintaining contact with the lower edge of the upper bar, it is subjected to the simultaneous attraction of both bars and is arrested. The opposing forces in the magnetic field are applied substantially equally to the two points of contact and at angles which urge the bearing into the slot, the mechanical obstruction provided by the edges of the bars increasing substantially the effectiveness of such forces.

The use of permanent magnets in the manner described insures permanent retention of the objects separated out of the material to be processed and avoids the necessity of an outside source of electrical energy with its attendant objections. The device has the further advantages that it is compact, self-contained and capable of retaining its effectiveness indefinitely and without attention.

I claim as my invention:

1. A device for separating vagrant fragments and objects of metal from a continuously flowing stream of non-magnetic material of granular or fibrous components comprising a board of non-magnetic material which is set at a predetermined inclination and provides a path along which said stream of material flows by gravity, said board having a shallow recess in its upper face, having openings at determined intervals which extend from said recess to its lower face and having a recess transverse to said shallow recess in the upper face of one or more of the webs of material between said openings, permanent

magnets fitted in said openings with their pole faces substantially flush with the bottom of said shallow recess, a pair of spaced magnetized bars of opposite polarity which are fitted in said shallow recess with their upper faces flush with the surface of said board whereby the non-magnetic material flowing along said board will pass first over one path and then over the other, a keeper fitted in said transverse recess below said magnetized bars and held by attraction against the under faces of said bars, and an insulating strip fitted within and closing the space between said bars.

2. A device for separating vagrant fragments and objects of metal from a continuously flowing stream of non-magnetic material of granular or fibrous components comprising a board of non-magnetic material which is set at a predetermined inclination and provides a path along which said stream of material flows by gravity, said board having a shallow recess in its upper face, having openings at determined intervals which extend from said recess to its lower face and having a recess transverse to said shallow recess in the upper face of one or more of the webs of material between said openings, permanent magnets fitted in said openings with their pole faces substantially flush with the bottom of said shallow recess, a pair of spaced magnetized bars of opposite polarity which are fitted in said shallow recess with their upper faces flush with the surface of said board whereby the non-magnetic material flowing along said board will pass first over one path and then over the other, a keeper fitted in said transverse recess below said magnetized bars and held by attraction against the under faces of said bars, and an insulating strip fitted within and closing the space between said bars.
